(57) **CLAIM**

The ornamental design for a toilet seat for children as shown and described.

DESCRIPTION

FIG. 1 is a front, right and top perspective view of a first embodiment of a toilet seat for children, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the toilet seat for children in a folded state of FIG. 1.

FIG. 10 is a front, right and top perspective view of a second embodiment of the toilet seat for children.

FIG. 11 is a rear, left and bottom perspective view thereof.

FIG. 12 is a front elevation view thereof.

FIG. 13 is a rear elevation view thereof.

FIG. 14 is a left side elevation view thereof.

FIG. 15 is a right side elevation view thereof.

FIG. 16 is a top plan view thereof.

FIG. 17 is a bottom plan view thereof.

FIG. 18 is another front, right and top perspective view of the toilet seat for children in a folded state of FIG. 10.

FIG. 19 is a front, right and top perspective view of a third embodiment of the toilet seat for children.

FIG. 20 is a rear, left and bottom perspective view thereof.

FIG. 21 is a front elevation view thereof.

FIG. 22 is a rear elevation view thereof.

FIG. 23 is a left side elevation view thereof.

FIG. 24 is a right side elevation view thereof.

FIG. 25 is a top plan view thereof.

FIG. 26 is a bottom plan view thereof.

FIG. 27 is another front, right and top perspective view of the toilet seat for children in a folded state of FIG. 19.

(Continued)

FIG. 28 is a front, right and top perspective view of a fourth embodiment of the toilet seat for children.

FIG. 29 is a rear, left and bottom perspective view thereof.

FIG. 30 is a front elevation view thereof.

FIG. 31 is a rear elevation view thereof.

FIG. 32 is a left side elevation view thereof.

FIG. 33 is a right side elevation view thereof.

FIG. 34 is a top plan view thereof.

FIG. 35 is a bottom plan view thereof.

FIG. 36 is another front, right and top perspective view of the toilet seat for children in a folded state of FIG. 28.

FIG. 37 is a front, right and top perspective view of a fifth embodiment of the toilet seat for children.

FIG. 38 is a rear, left and bottom perspective view thereof.

FIG. 39 is a front elevation view thereof.

FIG. 40 is a rear elevation view thereof.

FIG. 41 is a left side elevation view thereof.

FIG. 42 is a right side elevation view thereof.

FIG. 43 is a top plan view thereof.

FIG. 44 is a bottom plan view thereof; and,

FIG. 45 is another front, right and top perspective view of the toilet seat for children in a folded state of FIG. 37.

The dashed broken lines depict portions of the toilet seat for children that form no part of the claimed design.
